AUTOMOBILE VISOR EXTENSION SHADE

Danny L. Deaver, 2150 Cheryl Way, San Jose, Calif.

Filed Sept. 2, 1964, Ser. No. 81,567

Term of patent 14 years

(Cl. D14—6)

FIG. 1 is a perspective of the automobile visor extension shade showing my new design;

FIG. 2 is a top plan view;

FIG. 3 is an end elevational view of the right end of FIG. 2;

FIG. 4 is an end elevational view of the left end of FIG. 2;

FIG. 5 is a front elevational view extended and unfolded;

FIG. 6 is a top plan view of FIG. 5.

I claim:

The ornamental design for an automobile visor extension shade, as shown.
